UNITED STATES PATENT OFFICE.

ARTHUR H. INGLE AND WALLACE E. WARD, OF ROCHESTER, NEW YORK; SAID WARD
ASSIGNOR TO SAID INGLE.

APRON MECHANISM FOR LATHES.

1,345,676.

Specification of Letters Patent.

Patented July 6, 1920.

Application filed June 8, 1917. Serial No. 173,629.

To all whom it may concern:

Be it known that we, ARTHUR H. INGLE and WALLACE E. WARD, citizens of the United States, and both residents of Rochester, in the county of Monroe and State of New York, have invented an Improvement in Apron Mechanisms for Lathes, of which the following description, in connection with the accompanying drawings, is a specification, like characters on the drawings representing like parts in each of the several views.

This invention relates to lathes and particularly to the apron mechanism thereof with the feeding and operating connections carried thereby. A principal object of the invention is to provide means whereby in a type of lathe adapted for either thread cutting, or lathe operations involving the usual feeds of the tool carriage and slides, it is insured that the connections for thread cutting will not be operative at the same time that the connections for the usual carriage and slide feeds are operative. A further object is to provide improved operating connections from the lengthwise drive shaft or lead screw of a lathe to the tool carriage and tool slide for operating the same either for a relatively slow feed movement or for a rapid traverse, or for manual adjustment at will. A further object is to provide an improved construction of automatic stop for the feed movement operable at predetermined adjustable points along the ways of the machine. A still further object is to provide an improved construction and co-operative arrangement of a divided or opening nut for controlling a thread cutting feed along with shiftable clutch devices for controlling power transmission to effect the usual lathe feeds. The foregoing and other objects and features of the invention will be better understood from the following detailed description taken in connection with the accompanying drawings and will be thereafter pointed out in the appended claims.

Referring to the drawings:

Figure 1 is a front side elevation of a lathe constructed in accordance with our invention;

Fig. 2 is an enlarged lengthwise vertical section adjacent the front of the apron showing interior parts in elevation;

Fig. 3 is an enlarged horizontal section on line 3—3 of Fig. 1;

Fig. 4 is a transverse section on line 4—4 of Figs. 2 and 3;

Fig. 5 is a transverse section on line 5—5 of Figs. 2 and 3; and

Fig. 6 is a fragmentary elevation showing details of the clutch mechanism.

A lathe bed is indicated at 1 with a head stock 2, carriage ways 3, and a lead screw 4 splined to serve also as a drive shaft, all of which may be of usual or any suitable construction. The tool carriage 5 mounted on the ways 3 has a depending apron 6 which in accordance with our invention is extended at either side as seen at 7 to constitute a relatively wide support and housing for the mechanism to be described. The lead screw and drive shaft 4 has slidably keyed thereon a clutch hub 8 equipped at each side with friction rings 9 adapted to be expanded into operative engagement with either of the oppositely facing bevel pinions 10, 11 which have sleeve hubs 12 through which the shaft 4 passes, said hubs being journaled and held from endwise movement in sleeve bearings 13 carried by the apron. The pinions 10, 11 are selectively brought into driving engagement with the shaft 4 by a slipper sleeve 14 slidably fitted on the hub 8 and having tapered projections at its opposite sides adapted to expand one or the other of the friction rings within the pinions 10, 11 according to its position. The pinions 10, 11 are both in driving engagement with a bevel pinion 15 fixed on a short shaft 16 journaled in the apron and having rigid therewith a long spur pinion 17 which is in driving engagement with a large spur gear 18 journaled on a shaft 19 and having a long sleeve hub 20 integral or rigid therewith extending without the apron with a nut head 21 projecting in position to be engaged for sliding the gear 18 endwise. The shaft 19 has support at its inner end by being fixed as at 22 in the apron while the sleeve hub 20 has a external bearing 23 in an outer portion of the apron frame work. The gear 18 which is thus continuously driven by the pinion 17 throughout its range of sliding adjustment, is when slid to an intermediate position engaged with a pinion 24 fixed on a shaft 25 which is journaled in the apron and has fixed at its inner end a rack pinion

26 adapted to engage the rack 27 of the lathe bed. This transmission from the large gear 18 to the pinion 24 thus effects a rapid traverse of the carriage along the bed. For 5 effecting a relatively slow power feed movement of the carriage the gear 18 is slid fully inward where an internally toothed recess 28 is adapted to engage one end of and drive, a small wide faced pinion 29 loosely mounted 10 on the shaft 19. The pinion 29 drives a large gear 30 rigid with the pinion 24 and shaft 25, thus transmitting a relatively slow movement to the rack engaging pinion 26. For manually traversing the carriage a 15 pinion 31 engageable with the gear 30 is fixed at the inner end of a shaft 32 journaled in the apron and having at its outer end an operating hand wheel 33. The gear 18 is adapted to occupy an intermediate inoperative 20 position where it drives neither the pinion 29 nor the pinion 24, it being shown as occupying this position in Fig. 3. The gear 18 is also adapted to occupy a third operative position for operating the cross 25 feed of the tool slide. For this purpose it is adjusted fully outward, *i. e.*, to the position shown in dotted lines in Figs. 3 and 4, where it engages the cross feed pinion 34 for driving the cross feed screw 35 to operate 30 the cross slide 36 of the lathe. For moving the rod 38 to shift the clutch manually a hand lever 46 may be fixed to the shaft to which one of the bell crank levers 40 is secured, the shaft at the right side being projected forwardly for this purpose as indicated 35 at 46' in Fig. 3.

The sleeve 14 is operated to selectively engage either of the pinions 10, 11 with the shaft 4 for producing the feed movement in 40 either direction desired by a shipper yoke 37 fixed on a rod 38 pivotally connected at 39 at each end to a depending portion of bell crank levers 40 fulcrumed at 41 and having their other arms extending horizontally outward in opposite directions, equipped with 45 roller pins 42 engageable with recesses formed in stop blocks 43 adjustably fixed to the lathe bed. These recesses have conical portions 44 facing toward the roller pins 42 and leading to a central portion 45 with parallel sides that approximately fit said roller pins. Thus when clutch connections are made for either of the pinions 10, 11 to 50 impart feed movement as described, upon a predetermined travel of the carriage the clutch is moved to disconnect such feed and held in an intermediate neutral position as soon as the pin 42 engages the recesses of block 43 on the side toward which the carriage is moved. To adapt the lathe for 55 thread cutting or like uses, a divided or opening nut for engaging the screw shaft 4 is indicated at 47, this being composed of two halves connected for relative opening

and closing movement upon the screw 65 shaft; this connection being shown as by pivoted links 48 connected to be operated by an oscillating shaft 49 journaled in the apron and having a projecting operating handle 50. In accordance with our invention 70 this opening movement of the divided nut 47 is utilized to control the operation of the clutch shifting rod 38 in a manner now to be explained. For this purpose the upper half of said nut is formed with a radial recess having a relatively wide lower portion 51, with an intermediate portion 52 tapering at opposite sides inward to an upper contracted recess portion 53. The recess portion 53 is formed with parallel sides that 75 approximately fit a roller 54 carried on a pin 55 borne by the depending arm of the adjacent bell crank lever 40 as indicated at 56, said roller and the recess of said nut being relatively so arranged that as the 80 roller occupies said contracted recess portion 53 the rod 38 is thereby held in position to lock the clutch sleeve 14 in intermediate neutral position.

It may now be understood that so long as 90 the divided nut is open the clutch may be operated by shifting of rod 38 either automatically at the end of an operating movement of the carriage by engagement of one of the roller pins 42 with the recess 45, or 95 manually by the handle 46, at will, the roller pin 54 then operating in the wide lower portion 51 of the nut recess. When the lathe is to be used for thread cutting or the like, however, and the divided nut is therefore closed 100 on to the lead screw, should the clutch sleeve 14 have been left in either clutch engaging position, it is automatically shifted to intermediate neutral position by the inclined sides 52 and held in such intermediate 105 position by the narrow portion 53 of the nut recess engaging the roll 54, thus locking the clutch against any movement either manually or by the stops 43. Thus the possibility of accident that might result from 110 leaving both feeds engaged at once by a careless operator is entirely avoided. Further by the provision of the conical recess formations 44 leading to the contracted central portions 45 in the stops 43, it is insured 115 that the clutch sleeve 14 will be shifted definitely to central position and held therein at the predetermined limit of carriage movement so that possibility of either of the feed operating pinions 10, 11 being improperly 120 engaged is avoided. We are aware that the invention may be embodied in other specific forms as to various details thereof and we therefore desire the present embodiment to be considered as illustrative and not restrictive, reference being had to the appended claims rather than to the foregoing description to indicate the scope of the invention. 125

Having described our invention, what we claim as new and desire to secure by Letters Patent is:

1. Apparatus of the kind described, comprising a tool carriage equipped with a cross slide and with an apron, a power shaft extending lengthwise of the lathe, and operating mechanism for moving said carriage and said cross slide from said power shaft including a shiftable gear having gear elements coöperative therewith for moving said carriage at a relatively slow rate for feeding or at a higher rate for power traverse, or for moving said cross feed, said shiftable gear being selectively engageable with said gear elements in different shifted positions and being also shiftable to an inoperative position.

2. Apparatus of the kind described, comprising a lathe carriage, a power shaft extending lengthwise of the lathe, and operating mechanism for moving said carriage from said shaft, including a shiftable gear having a connection coöperative therewith for effecting a relatively slow feed movement, said connection consisting in a pinion adapted to fit into a recess in a side of said gear, and another gear connection selectively engageable with said shiftable gear for effecting a rapid traverse, said gear being also shiftable to a third inoperative position.

3. Apparatus of the kind described, comprising a lathe carriage, operating means therefor, a clutch and an opening nut selectively engageable with said operating means to move the carriage at different rates, and a shifter for said clutch having a member associated therewith extended to coöperate with said nut, said nut having beveled faces arranged to engage said mem-

ber to move said clutch to inoperative position as said nut is moved to engaging position.

4. Apparatus of the kind described, comprising a lathe carriage equipped with a depending apron, operating mechanism for said carriage including a clutch device and an opening nut selectively engageable to move the carriage, and means including a shifter rod, and lever devices coöperative with said opening nut to shift said clutch device to inoperative position by the movement of said nut to engage the same, said nut having a recess formation with beveled sides adapted to act on said lever to shift the same for moving said clutch device to inoperative position as the nut is moved to engaging position.

5. Apparatus of the kind described, comprising a tool carriage equipped with an apron, a combined power shaft and lead screw extending lengthwise of the lathe, operating connections including a clutch device for moving said tool carriage in either direction, a shifter rod for said clutch device, bell crank levers having oppositely extending arms connected to said shifter rod, and an opening nut carried by said apron to engage said lead screw for thread cutting and the like, said opening nut having a formation carried thereby engageable with one of said bell crank levers to hold it in position for locking said clutch device inoperative as said nut is closed on said lead screw and releasing it to permit operation of said clutch device as said nut is opened.

In testimony whereof, we have signed our names to this specification.

ARTHUR H. INGLE.
WALLACE E. WARD.
